FOLDING UMBRELLA

Heinrich J. Kiel, Solingen-Wald, and Gunter H. Gran-
rath, Solingen-Weyer, Germany, assignors to Korten-
bach & Rauh K. G., Solingen-Weyer, Germany

Application August 18, 1954, Serial No. 450,631

Claims priority, application Germany August 21, 1953

5 Claims. (Cl. 135—25)

The present invention relates to a folding umbrella having a shank composed of sections telescopically movable into each other and having foldable ribs. The heretofore known folding umbrellas of this type are relatively awkward in operation, especially when the umbrella is to be placed into readiness for use. Customarily, when opening up the umbrella, the umbrella has to be held upwardly so that the folded back outer rib sections, together with the umbrella cover, will drop down. During this operation, it is also in most instances necessary manually to unfold some of the ribs.

It is, therefore, an object of the present invention to provide a folding umbrella which will overcome the above-mentioned drawbacks.

It is another object of this invention to provide a folding umbrella which can be opened up in a far simpler manner than was possible with umbrellas heretofore known.

It is a still further object of this invention to provide a folding umbrella which can easily be opened up without having to hold the umbrella shank in a vertical direction with the rib sections up.

These and other objects and advantages of the invention will appear more clearly from the following specification in connection with the accompanying drawings, in which

Fig. 1 illustrates a portion of an umbrella according to the invention with the rib shown therein in completely opened up position.

Fig. 2 illustrates an intermediate step between the unopened and fully opened position of the umbrella.

Fig. 3 shows the end of the inner rib portion on a scale somewhat larger than that used in Fig. 2.

Fig. 4 shows a portion of an umbrella somewhat modified over that of Fig. 1 and provided with a slide slidable on the rib lever.

Fig. 5 is an intermediate position similar to that of Fig. 2 but for the embodiment of the umbrella of Fig. 4.

Fig. 6 represents the end of the inner rib of the umbrella of Fig. 4 but on a larger scale than that used in Fig. 4.

Fig. 7 shows a view of the slide.

Fig. 8 is a cross-section taken along the line VIII—VIII of Fig. 7.

Fig. 9 is a modification of the slide of Fig. 7.

Figs. 10 and 11 illustrate a further embodiment of the invention.

General arrangement

In order to simplify the handling of a folding umbrella according to the present invention, a pulling means, for instance, synthetic thread, is arranged between the inner end of the outer rib section and rib lever and a portion of the inner rib lever pivotally connected to the inner rib section. Due to this arrangement, when opening up the umbrella, the said pulling means exerts a force upon the outer rib section so that the latter is folded toward the outside. Thus, all outer rib sections will not only safely and surely move into

2

their opened up position, but it is also possible to open up the umbrella in different positions, for instance, in a horizontal position, because it is not necessary to make use of the gravity action by holding the umbrella upright to cause the outer rib sections to fold downwardly.

In order to guide the pulling means, the latter is, for instance, passed or threaded through an opening at the outer end of the inner rib section. This results in a very simple guiding for the pulling means. Similarly, the rib lever has its outer end provided with a bore or the like through which one end of the pulling means is passed.

In order further to improve the action of the pulling means, the pulling means may, in conformity with a further embodiment of the invention, be connected with a slide slideable upon an end section of the rib lever, in which instance the pulling means is not directly connected or fastened to the rib lever. This arrangement yields a very good adjustability of the pulling means with regard to its action upon the outer rib section. Preferably, an abutment, for instance, a pin, clamping ring or the like is arranged on the rib lever. Such an abutment will prevent the slide with the pulling means from sliding on the rib lever too far toward the runner on the shank.

Advantageously, the slide is simultaneously used for fastening the loop-shaped pulling means. The ends of the thread serving as pulling means are threaded through holes in the ears of the slide which represents a bent sheet metal element. However, it is also possible to pass the thread through an opening in the slide and an aperture in the outer rib section and to interconnect the ends of the thread by means of a sheet metal clamp or the like. Also in this manner a very good closure of the loop is obtained.

Structural arrangement

Referring now to the drawings in detail and Fig. 1 thereof in particular, the shaft of the folding umbrella consists, for instance, in customary manner of the two sections 1 and 2 which can be moved into each other in a telescopic manner. Pivotally connected to the top 3 of the umbrella are the inner rib sections 4 which are linked to the runner 6 by means of the rib lever 5. The outer ends of the inner rib sections 4 have pivotally connected thereto the outer rib sections 7.

In order to obtain an automatic opening and folding of the outer rib sections, according to the invention there is provided a pulling means 8, for instance, a synthetic thread. As will be seen from Fig. 1, the said pulling means 8 extends from approximately the inner end of the outer rib section 7 to the outer end section of the rib lever 5. The thread 8 is passed through an opening 9 (Fig. 3) of the inner rib section 4 and extends, for instance, in a loop-like manner around the inner end of the outer rib section 7.

Fig. 2 illustrates by dashed lines how the outer rib section is tilted away from the inner rib section. When the runner 6 is moved towards the top 3 of the umbrella, the thread 8 is tensioned so that it exerts a force upon the outer umbrella section 7 in order to cause the latter to swing into alignment with the inner rib section 4. This pulling effect exerted upon the outer rib section remains maintained when the umbrella is completely folded up.

The elements of the modifications shown in Figs. 4 to 10 which correspond to the elements of Fig. 1 are designated with the same reference numerals used in Figs. 1 to 3 with the exception that the reference numerals of Figs. 4 to 6 have the additional character "a," while the

corresponding reference numerals of Figs. 10 and 11 have the additional character "b."

According to the invention, the thread serving as a pulling means is fixedly connected to the inner end of the outer rib section. This may be done, for instance in conformity with the embodiment of Fig. 6, by passing the thread through a corresponding opening 10 in the flat end of the outer rib section 7a. In order to improve the effect of the pulling means, a slide 11 is slidably mounted on the rib lever 5a. In this instance the thread 8 represents a loop and both ends of said loop are connected with each other within the slide 11 (see Fig. 7). The slide 11 is provided with two ears 12 which have apertures 13 through which the ends of the thread 8 are passed a number of times, as is clearly visible from Fig. 7.

In order to prevent the slide 11 from sliding too far inwardly toward the runner 6 when the umbrella is in its folded together position, the rib lever is provided with an abutment which according to the embodiment of Fig. 7 is represented by a small pin 14. In conformity with the embodiment shown in Fig. 9, the rib lever 5b has mounted thereon an abutment in form of a clamping ring 15 which is passed around and fixedly clamped to the rib lever 5b.

In order to facilitate the fastening of the ends of the thread, it is also possible as shown in Fig. 9 to provide the slide 11 with one aperture 13 only and to pass the loop through the aperture 13. In this instance, the two ends of the thread are then held together by a sheet metal clamp 16 through which not only the two ends of the loop but also the other loop portion may be passed, thereby holding the loop together. The clamp 16 may preferably be so designed that the end surfaces of this clamp are bent outwardly as shown in Fig. 9 so that the sharp edges of the clamp cannot exert a shearing force upon the thread 8, which preferably is made of synthetic material.

The folding together of an umbrella according to the present invention is effected in the manner customary with folding umbrellas heretofore known, inasmuch as the pulling thread 8 will exert no function whatsoever during this folding together operation.

Referring now to the embodiment shown in Figs. 10 and 11, the pulling means represented by the thread 17 is passed through a bore in the slide 11d, which slide is slidable on the rib lever 5b between the abutment clamp 15 and the pivot carrying clamp 18 on the inner rib section 4b. The thread 17 furthermore passes through a bore at the outer end 19 of the outer rib section 7b while the ends of the thread 17 are likewise held together by a clamp 16 which may also extend around the outer loop branch. For further guiding the said pulling means, the latter may also be passed through a bore at the outer end 20 of the inner rib section 4. By means of this arrangement, there is thus obtained a pulling effect by the thread 17 upon the outer ends of the outer rib sections.

It is, of course, to be understood that the present invention is by no means limited to the particular embodiments shown in the drawings but also comprises any modifications within the scope of the appended claims.

What we claim is:

1. In combination in a folding umbrella: a shank, an inner rib section, means hingedly connecting one end of said inner rib section to said shank, an outer rib section hingedly connected to the other end of said inner rib section, a runner slidably mounted on said shank and movable selectively in a first direction for opening up the

umbrella or in a second direction for collapsing and folding together the umbrella, rod means having one end hinged to said runner and having its other end hinged to said inner rib section, said inner rib section being provided with a bore adjacent its outer end, and pulling means operatively connected to said rod means and passing through said bore of said inner rib section while operatively engaging the adjacent portion of said outer rib section to thereby operatively connect said outer rib section with said rod means, said pulling means being operable automatically in response to the movement of said runner in said first direction to exert a pulling force upon said outer rib section for bringing the latter into axial alignment with said inner rib section.

2. In combination in a folding umbrella: a shank, an inner rib section, means hingedly connecting one end of said inner rib section to said shank, an outer rib section hingedly connected to the other end of said inner rib section, a runner slidably mounted on said shank and movable selectively in a first direction for opening up the umbrella or in a second direction for collapsing and folding together the umbrella, rod means having one end hinged to said runner and having its other end hinged to said inner rib section, a slide slidably mounted on said rod means, and pulling means having one end portion connected to said slide and having its other end portion connected to the inner end portion of the outer rib section.

3. An umbrella according to claim 2 in which said rod means is provided with an abutment means for limiting the movement of said slide toward said runner.

4. In combination in a folding umbrella: a shank, an inner rib section, means hingedly connecting one end of said inner rib section to said shank, an outer rib section hingedly connected to the other end of said inner rib section, a runner slidably mounted on said shank and movable selectively in a first direction for opening up the umbrella or in a second direction for collapsing and folding together the umbrella, rod means having one end hinged to said runner and having its other end hinged to said inner rib section, a slide slidably mounted on said rod means, and provided with an ear having bores therethrough, and pulling cord means forming a loop and having its ends threaded through said bores while the opposite loop portion of said pulling cord means engages said outer rib section.

5. In combination in a folding umbrella: a shank, an inner rib section, means hingedly connecting one end of said inner rib section to said shank, an outer rib section hingedly connected to the other end of said inner rib section, a runner slidably mounted on said shank and movable selectively in a first direction for opening up the umbrella or in a second direction for collapsing and folding together the umbrella, rod means having one end hinged to said runner and having its other end hinged to said inner rib section, a slide slidably mounted on said rod means, said slide being provided with a passage, said outer rib section also being provided with a passage adjacent one end thereof, cord means passed through said first mentioned and said second mentioned passage so as to form a complete loop, and means for clamping and holding the free ends of said loop together.
